FIG' 1

FIG' 2

INVENTOR.

William Lorenz

UNITED STATES PATENT OFFICE

161,945

WISHING WELL MUSICAL TOY BANK

William Lorenz, Los Angeles, Calif.

Application October 4, 1950, Serial No. 12,450

Term of patent 14 years

(Cl. D34—11)

To all whom it may concern:

Be it known that I, William Lorenz, a citizen of the United States, residing at 2719 Clyde Avenue, in the county of Los Angeles and State of California, have invented a new, original, and ornamental Design for Wishing Well Musical Toy Bank, of which the following is a specification, reference being had to the accompanying drawing, forming part thereof.

Figure 1 is a view in perspective as viewed from the front of the wishing well musical toy bank, embodying my new design; and

I claim:

The ornamental design for a wishing well musical toy bank, substantially as shown.

WILLIAM LORENZ.
